United States Patent Office.

FRANKLIN T. GILBERT, OF ELGIN, ILLINOIS.

Letters Patent No. 61,731, dated February 5, 1867.

IMPROVEMENT IN WATER ELEVATORS.

The Schedule referred to in these Letters Patent and making part of the same.

TO ALL WHOM IT MAY CONCERN:

Be it known that I, FRANKLIN T. GILBERT, of Elgin, in the county of Kane, and State of Illinois, have invented certain new and useful Improvements on Water Elevators; and I do declare that the following is a full, clear, and exact description of the construction and operation of the same, reference being had to the accompanying drawings, making a part of this specification, in which—

Figure 1 is a front elevation.

Figure 2 is a sectional view, showing the lever B, balls H H', and the lever P P' separated at the joint.

Figure 3 shows the movable spool i.

The nature and objects of my invention consist in an improved automatic device for reversing the motion of water elevators having two buckets, and in the combinations hereinafter mentioned.

To enable others skilled in the art to make and use my invention, I will proceed to describe its construction and operation.

The curb M, shaft E, cylinders T T', so arranged as to revolve on the shaft E; the gear-wheels L L' N, standard F, collar S, so arranged as to revolve with the shaft, but capable of lateral adjustment, and provided at the centre with a ledge or projection, are all made and arranged in the usual manner, except that I make the collar with ratchet-teeth at the ends, and like teeth on the ends of the hubs of the wheels. My device for shifting the collar S is as follows: B is a tubular lever, about three inches in diameter, and in length adapted to the size of the curb. This lever is attached to the standard F by the bolt u, so that the lever moves freely on the bolt, and it must be so adjusted that the ledge h on the collar S will enter the slot n in the upper end of the lever P. P P' compose a flat-jointed lever, having a slot, n, in the upper end to receive the ledge h on the collar S. P' should be cast or made as a part of or be firmly attached to the lever B. The joint in the lever P P' is a double knuckle joint, and is placed at a point about one-third of the distance from the lever B to the upper end of the lever P. In the hollow lever B are two metallic balls, or other suitable balls or weights, of such size that they cannot pass the bolt u, and of sufficient weight to operate the levers, the weights to be of such shape as will permit them to pass freely through the lever B. The ends of the lever B must be so secured that the weights cannot roll out. The lever B, the buckets, and the device for emptying the same, are to be so placed and arranged that each bucket, as it is emptied, will come in contact with its end of the lever B, and raise it far enough above the horizontal position to cause the weights H H' to change their places and pass, one from the centre to the end, the other from the end to the centre of the lever B. The lever B must be so placed that the cross-bar O will not interfere with its operation. The shoulders of the knuckle joint must be placed at such distance apart that the lever B can be operated sufficiently to cause the weights H H' to change their position without acting upon the collar S; and at the moment that the bucket is emptied, the shoulders towards the raised end of the lever B should be in contact, the jointed lever then becomes rigid and the collar S is moved. The operation of this device in shifting the collar S will be readily seen. When a bucket is raised and emptied, it comes in contact with and raises its end or arm of the lever B, so that the weight in that arm of the lever rolls to the centre, while the weight in the other arm of the lever rolls to the end. Upon reversing the motion of the shaft a trifle, the pressure upon the teeth on the collar S is removed, and thereupon the weight in the depressed end of the lever B, acting upon the collar S through and by means of the jointed lever P, shifts the collar S, and it is held in gear by the weight at the end of the lever B. My device for presenting the buckets in a proper position to be emptied is as follows: The rod t is firmly fastened to the sides of the curb, being a little below and in front of the cylinders T T'. On this rod I place two movable friction-rollers, in the middle of each of which is a groove, j, of sufficient size to receive and hold the rope. The rollers have a broad flange on each end, and in size are to be adapted to the chain or strap used on the bucket, which must be flat. The knob k on the buckets, and the emptying bail x, are arranged in the usual manner. The operation of this device is as follows: As the rope passes from one end to the other of the cylinders T T' it moves the roller j along on the rod t, the rope being held in the groove j by the weight of the bucket. As the bucket is raised, the chain or strap e will pass over the roller j, between the flanges, and the bucket will be held in the proper position for the knob k to be caught by the emptying bail x. I prefer to have the strap o made of metal. It is not essential to the working of my device that a tube be used; other forms can be used if made so as to hold the weights and permit their free motion.

In the use of my device for shifting the collar S, I do not confine myself to water elevators, but claim said device for the purpose of reversing motion in all cases to which it can be applied.

What I claim as my invention, and desire to secure by Letters Patent, is—

1. The hollow double lever B, when operated or held in place by balls, substantially as specified.
2. The jointed lever P P', constructed substantially as set forth, in combination with the weighted lever B.
3. The combination and arrangement of the double weighted lever B, jointed lever P P', and ratchet S, with the loosely-revolving cylinders T, mitre-wheels L L' N, well cords, straps e, friction-roller i, buckets A, and discharging bail x, when constructed and arranged substantially as specified.

F. T. GILBERT.
